UNITED STATES PATENT OFFICE

PHILIP L. DAVIS, OF NEW YORK, N. Y., ASSIGNOR TO KEYSTONE TRANSPORTATION COMPANY, INC., OF NEW YORK, N. Y.

DESIGN FOR AN AUTOMOBILE RADIATOR CAP OR ARTICLE OF SIMILAR NATURE

Application filed May 7, 1931. Serial No. 39,744. Term of patent 3½ years.

To all whom it may concern:

Be it known that I, PHILIP L. DAVIS, a citizen of the United States, residing in New York, in the county of New York and the State of New York, have invented a new, original, and ornamental Design for an Automobile Radiator Cap or Article of Similar Nature, of which the following is a specification, reference being had to the accompanying drawings, forming a part thereof.

Figure 1 is a side elevational view of an

automobile radiator cap showing my new design.

Fig. 2 is a top plan view thereof. The portions shown in dotted lines are mere repeats of those shown in full outline.

I claim:

The ornamental design for an automobile radiator cap or article of similar nature, as shown.

In testimony whereof I affix my signature.

PHILIP L. DAVIS.
